(57) **CLAIM**

The ornamental design for an electric scooter, as shown and described.

DESCRIPTION

FIG. 1 is a top, front, right side perspective view of an electric scooter, showing my new design;

FIG. 2 is a bottom, rear, left side perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is an enlarged view of a portion labelled 9 in FIG. 1;

FIG. 10 is an enlarged view of a portion labelled 10 in FIG. 1;

FIG. 11 is an enlarged view of a portion labelled 11 in FIG. 1;

FIG. 12 is an enlarged view of a portion labelled 12 in FIG. 1;
